UNITED STATES PATENT OFFICE.

JAMES R. COE, OF WATERBURY, CONNECTICUT, ASSIGNOR TO THE AMERICAN BRASS COMPANY, OF WATERBURY, CONNECTICUT, A CORPORATION OF CONNECTICUT.

ROLLING MILL.

Application filed August 7, 1925. Serial No. 48,730.

This invention relates to rolling mills, and has for an object to provide improved means to obtain the necessary stiffness with the use of rolls of comparatively small diameter.

5 It is also an object of the invention to so mount the working rolls and the stiffening and supporting means therefor that one of the rolls and its stiffening means may be adjusted as a whole or as a unit relative to 10 the other working roll to secure the required relative adjustment between the rolls.

It is a further object of the invention to so construct the mounting and stiffening means for the working rolls that they may 15 be mounted in the standard housings used in this type of device, and therefore, rolls provided with my improved stiffening and supporting means may be substituted for larger rolls mounted in the housings without 20 out reconstructing the housings.

With the foregoing and other objects in view, I have devised the construction illustrated in the accompanying drawings, and which in the preferred construction comprises 25 a pair of working rolls each of which is backed and supported by two sets of rotating supporting members, the supporting members for each roll being mounted on a heavy casting extending between the housings. The rotating members are mounted to 30 rotate on stationary shafts mounted on the castings and the shafts are supported thereby at a number of different positions throughout the lengths of the shafts, the 35 rotating members being mounted between the shaft supports. These elements are so constructed and arranged that a roll, the supporting casting, the shafts and the rotating 40 supporting members constitute a unit, and one of these units is so mounted that it is adjustable as a whole relative to the other unit in a vertical plane, this adjustment being secured by the usual means of lifting rods actuated by levers and counterweights 45 or springs, in conjunction with the usual adjusting screws.

Referring to the accompanying drawings, Fig. 1 is a side elevation of a rolling mill showing my improved construction.

50 Fig. 2 is a transverse vertical section through the same substantially on line 2-2 of Fig. 1 but drawn to a larger scale.

Fig. 3 is an end elevation of the mill looking from the right of Fig. 1, and

55 Fig. 4 is a detailed view showing one of but may be secured in adjusted position by

the working rolls in elevation and the stiffening and supporting means therefor in vertical section.

In rolling mill practice frequently very high pressures are required and rolls to withstand these pressures and not yield or spring an objectionable amount must be of a very large diameter, which makes them expensive and also difficult to handle. These larger rolls are also objectionable for certain work because, on account of the small angle at the 60 rolling point between the rolls, it is difficult to secure the required reduction in the metal being rolled.

To overcome these objections mills have 70 been made with working rolls of relatively small diameter in order to secure a larger angle at the rolling point between the rolls and give the required reduction, and these rolls have been backed or supported by 75 means of separate idling rolls to prevent excessive springing of the working rolls and to give the required strength, but as these backing rolls are supported in substantially the same way as the working rolls they 80 must be of a large diameter to give the required strength and stiffness, and they require specially designed housings or frames.

Attempts have also been made to overcome 85 these objections and support the work rolls by means of a plurality of rotating elements engaging the surface of the roll and mounted on a separate shaft, but as this shaft was supported at its ends only, in order to secure the required stiffness, it had to be as 90 large as the backing rolls required in the previous construction.

I have found that by supporting the working roll on a plurality of spaced rotating members mounted on a stationary shaft which is supported throughout its length between the rotating elements, I can use a relatively small shaft and can produce a construction which will give the required strength and stiffness to the working roll and which does 100 not require specially designed housings or frames, but may be mounted in the regular housings.

In the accompanying drawings is shown a mill involving my improved construction. 105 In this mill 10 represents a pair of the usual housings or frames mounted in spaced relation, and the usual supporting rails 11 on which they are longitudinally adjustable, but may be secured in adjusted position by 110

any suitable means. Mounted in these housings are a pair of working rolls 12 which are driven from any suitable source of power by the couplings 13, the ends of the roll 5 necks being squared as shown at 14, as in the usual construction. These working rolls are each backed and thus stiffened by two sets of rotating supporting members 15. There may be but a single set for each roll, 10 but I prefer to use two sets, as shown in Fig. 2, positioned on opposite sides of the vertical plane through the axis of the roll to carry the lateral thrust as well as the vertical thrust. There may be any desired 15 number of these rotating members engaging the surface of the working rolls and spaced at suitable distances throughout the length of these rolls, in the present drawing five being shown, and each set of these members 20 is mounted to rotate on a stationary shaft 16 carried by a support 17 mounted in the housings and extending between them. The shafts are preferably reduced in diameter somewhat between these rotating members 25 as indicated at 18, and they are supported at these reduced portions directly on the support 17 as shown at 19 in Fig. 4. These supports may be integral with the support 17 or may be separate blocks as desired, and 30 the rotating members 15 preferably rotate on antifriction bearings on the shaft, such as ball or roller bearings 20.

The supports 17 are shown as heavy castings which extend longitudinally between 35 the two housings. In the present construction the lower casting is seated at its opposite ends in the housings and rests on the lower walls 21 of the openings 22 in the housings. The upper casting 17 is guided 40 at its opposite ends for vertical movement in these openings, the side walls of the openings forming guides for the casting and maintain it in proper position. These two castings are of similar construction and are 45 strengthened to give them the required vertical stiffness by the ribs 23. They are also provided with lateral ribs 24 to give them the required lateral stiffness. It will be apparent that with this construction and ar- 50 rangement the working rolls are provided with bearing members which back the roll and support it at suitably spaced distances throughout the length of the roll, and the strain on the roll incident to the rolling operation tending to bend it laterally is transmitted to the rotating members 15, by these members to the shaft 16, and by the shaft to the heavy castings or supports 17. Thus the working rolls may be given any diameter which is the most suitable for the particular work to be performed, having in mind the desired angle between the rolls at the rolling space, and the strains are taken up by the heavy castings 17.

The shaft 16 may be held in position in

the support 17 by suitable means such as caps 25 and 26, which are secured to the casting by any suitable means, such as the screws 27, and extend over the reduced portions of the shaft to hold the shaft in position. They may also be used to assist in retaining the roller bearings 20 in proper position.

The supports for the two rolls are so constructed and arranged that each working roll, the rotatable supporting members, the shaft on which these members are mounted and the supporting casting therefor comprise a separate unit, and one of these units, the upper one in the present instant, is mounted so that it is adjustable as a whole relative to the lower unit to give the required adjustments between the two working rolls for rolling various thicknesses of metal and so forth. To accomplish this, in the present construction the upper bearing block 28 for the reduced necks of the upper roll, which blocks are guided in the openings 22 in the housing, are supported by rods 29 which extend upwardly from below the housing where they are supported by the usual lever and counterweights or the heavy springs 30. These springs are mounted on a support 31 carried on the under side of the housing by the bolts 32 and bear at their upper ends against collars 33 secured to the rods 29 and thus tend to lift these rods. These rods carry suitable nuts 34 which engage the lower sides of the blocks 28 and thus tend to lift the upper working roll 12, the rotating backing members 15 therefor, the upper shaft 16 and the upper supporting casting 17 as a unit. The upward movement of this unit is controlled by the usual adjusting screws 35 mounted in the tops of the housings and engaging the casting 17. It will thus be apparent that the springs 30 acting through the rods 29 maintain the upper working roll against the backing members 15, and maintain the roll, these members and the supporting casting therefor in the same relative position, and that these elements by the coaction of the adjusting screw with these rods 35 springs allow adjustment of this unit as a whole and without changing in any way the relative positions of the elements in the unit, and furthermore, that this unit may be adjusted in a vertical plane relative to the lower working roll. The lower blocks 36 are provided to form upper bearings for the necks of the lower working roll through which the rods 27 extend. Bolts 37 extend through and between the two bearings and carry springs 38 reacting at their opposite ends against these two bearings and tend to separate the same and hold the lower working roll in proper position on the supporting and backing members 15.

It will be apparent from the foregoing

- that with the construction and arrangement described I can use working rolls of relatively small diameter, and can secure the necessary stiffness by means of the supporting 5 and backing members 15 supported in proper position by the supporting castings 17. By mounting the cluster or group consisting of a working roll and its rotating backing members in one big casting, they can be adjusted as a whole and the various elements 10 can be held in proper relation to each other, and the change in the relative positions of the various elements under stress is reduced to a minimum.
- 15 Having thus set forth the nature of my invention, what I claim is:
1. In a rolling mill, a working roll, a plurality of spaced supporting members for said roll arranged to engage the surface 20 thereof, a shaft extending longitudinally of the roll on which said supporting members are mounted to rotate, and supporting means for the shaft between said members.
  2. In a rolling mill, a working roll, a support at one side of said roll, a stationary shaft extending longitudinally of the roll mounted on said support and supported thereby at a plurality of spaced positions, and a plurality of spaced supporting members 25 for the roll mounted to rotate on the shaft between said supporting positions.
  3. In a rolling mill, a working roll, a support at one side of said roll, a pair of stationary spaced shafts carried by said support extending longitudinally of the roll and supported thereby at a plurality of spaced positions, and a plurality of spaced supporting members for the roll mounted 30 to rotate on each shaft between the supports for the shaft.
  4. In a rolling mill, a working roll, a support at one side of the roll, a plurality of rotating supporting members for the roll mounted on said support, said members being spaced from each other and engaging the surface of the roll at spaced positions throughout its length, and supporting means for the members on the support located between adjacent members.
  5. In a rolling mill, a working roll, a support at one side of the roll, a pair of spaced shafts mounted on the support and extending longitudinally of the roll, a plurality of supporting members for the roll mounted 55 to rotate on each shaft and spaced from each other longitudinally of the roll, and means for supporting the shafts between adjacent members.
  6. In a rolling mill, a pair of spaced 60 housings, a working roll mounted in the housings, a support mounted in the housings and extending therebetween at one side of the roll, a shaft mounted on said support and extending longitudinally of the roll, a plurality of spaced supporting members for the roll mounted to rotate on said shaft, and means on the support for supporting the shaft between adjacent members.
  7. In a rolling mill, a pair of spaced 70 housings, a pair of superimposed working rolls mounted in said housings, a support extending between the housings at one side of each roll, a plurality of individual supporting members for each roll spaced from each other longitudinally of the rolls and rotatably mounted on the supports, supporting means on the support for the members and located between adjacent members, and means for adjusting one of the rolls, its supporting members and the support for 75 said members as a unit.
  8. In a rolling mill, a pair of spaced 80 housings, a working roll mounted in said housings, a support extending between the housings at one side of the roll, a shaft extending longitudinally of the roll mounted on the support and supported thereby at a plurality of spaced positions throughout its length, and a plurality of supporting members rotatably mounted on the shaft between 85 said supports for the shaft and engaging the surface of the roll.
  9. In a rolling mill, a pair of spaced 90 housings, a working roll mounted in said housings, a support extending between the housings, at one side of the roll, a shaft extending longitudinally of the roll mounted on the support and supported thereby at a plurality of spaced positions throughout its length, a plurality of supporting members 95 for the roll rotatably mounted on the shaft between said supports for the shaft, and means for adjusting the roll, the support, the shaft and the supporting members as a unit.
  10. In a rolling mill, a pair of spaced 100 housings, a working roll mounted in the housings, a support extending between the housings at one side of the roll, a shaft extending longitudinally of the roll reduced in diameter at a plurality of spaced positions 110 and supported on the support at said reduced portions, and a plurality of supporting members engaging the roll and mounted to rotate on the shaft between said reduced portions.
  11. In a rolling mill, a pair of spaced 115 housings, a working roll mounted in the housings, a support extending between the housings at one side of the roll, a stationary shaft mounted on the support at a plurality of spaced positions throughout its length and extending longitudinally of the roll, a plurality of supporting members for the roll mounted to rotate about the shaft between said positions, and antifriction bearings between said members and the shaft.
  12. In a rolling mill, a pair of superimposed working rolls, a pair of spaced housings, a support extending between the housings above and below the rolls, a pair of 125 130 supporting members for each roll spaced from each other longitudinally of the rolls and rotatably mounted on the supports, supporting means on the support for the members and located between adjacent members, and means for adjusting one of the rolls, its supporting members and the support for said members as a unit.

- spaced stationary shafts carried by each support extending longitudinally of the rolls and supported on the support at spaced positions along their lengths, supporting members for the rolls mounted to rotate on said shafts between said supporting positions; and means for adjusting one of the rolls, the supporting members therefor and their support as a unit.
13. In a rolling mill, a pair of spaced housings, a working roll between the housings, a rigid support extending between the housings at one side of the roll and mounted at its ends in the housings, a stationary shaft 10 extending longitudinally of the roll and supported by said support at a plurality of spaced positions throughout substantially its entire length, and a plurality of supporting members for the roll engaging the surface thereof and mounted to rotate on the shaft 20 between said supports for the shaft.
14. In a rolling mill, a pair of spaced housings, a working roll between the housings, a rigid support extending between the housings at one side of the roll and mounted 25 at its ends in the housings, two sets of backing members for the roll engaging the surface thereof and mounted to rotate independently about axes extending longitudinally of the roll and the individual elements 30 of each set being spaced from each other longitudinally of the roll, said backing elements being provided to support the roll throughout substantially its entire length, and means between the individual elements 35 for supporting them on said support.

In testimony whereof I affix my signature.
JAMES R. COE.
